UNITED STATES PATENT OFFICE

138,599

DESIGN FOR A VALVE FOR MUD PUMP LINES

Philip M. Rea, Oklahoma City, Okla.

Application July 9, 1943, Serial No. 110,806

Term of patent 14 years

(Cl. D91—1)

To all whom it may concern:

Be it known that I, Philip M. Rea, a citizen of the United States, residing at Oklahoma City, in the county of Oklahoma and State of Oklahoma, have invented a new, original, and ornamental Design for a Valve for Mud Pump Lines, of which the following is a specification, reference being had to the accompanying drawings, forming part thereof, and in which:

Figure 1 is a side elevational view of a valve for mud pump lines, showing my new design;

Figure 2 is an elevation as viewed from the right hand end of Figure 1;

Figure 3 is a side elevation as viewed from the right hand end of Figure 2;

Figure 4 is a perspective view thereof; and

Figure 5 is a top view thereof on a reduced scale.

I claim:

The ornamental design for a valve for mud pump lines, as shown.

PHILIP M. REA.
